P. F. VAN HALDER

SIGNAL FOR AUTOMOBILES

Filed Sept. 24, 1924

Inventor

Peter F. Van Halder.

Larry T. Tracy, Attorney at Law

UNITED STATES PATENT OFFICE.

PETER F. VAN HALDER, OF GREEN BAY, WISCONSIN.

SIGNAL FOR AUTOMOBILES.

Application filed September 24, 1924. Serial No. 739,576.

My invention relates to signals for automobiles and the object of the invention is to provide a simple device which will be normally inoperative and may be easily brought into operative position without requiring the occupant of the car to leave the same or protrude any portion of his body from the car. Another object of the invention is to provide a simple device whereby the occupant of the car may readily signal other motorists of his intention to stop or to change the direction of his travel, and, more specifically, an object of the invention is to provide a device which may be mounted upon the body of the vehicle and manipulated from inside the vehicle so as to be brought into an operative position and automatically set so as to attract the attention of either approaching or following motorists. The invention is illustrated in the accompanying drawing and will be hereinafter fully set forth.

In the drawing:—

Figure 1 is a perspective view of a motor vehicle having my signal mounted thereon, the signal being shown in inoperative position;

Fig. 2 is an enlarged sectional elevation showing the signal in operative position;

Fig. 3 is an enlarged elevation of the inside of the door of the vehicle showing parts of the signal mechanism.

Fig. 4 is a fragmentary sectional view taken on the line 4—4 of Fig. 3 with the handle of the operating lever engaged with the latch.

The signal is illustrated as applied to a closed car 1 but it will be understood, of course, that it may be applied to an open car.

In carrying out the invention, I secure a bracket 2 upon the outer side of the door 3 of the vehicle, and to this bracket I pivotally attach one end of a stem or arm 4 which is preferably hollow and carries at its outer end a tubular casing 5 extending at a right angle to the stem or arm. Normally the arm or stem 4 is carried in the pendent position illustrated in Fig. 1 with the tubular casing 5 resting against the side of the door but when the signal is to be displayed the arm is swung upwardly to the horizontal position shown in Fig. 2, extending laterally from the door and having the housing or casing 5 disposed in a horizontal position parallel with the side of the door. A lens 6 is fitted in each end of the casing

5, and these lenses are preferably colored red so that they will be easily seen and will readily attract attention when the signal is in the operative display position. A small electric lamp, indicated by dotted lines at 7 in Fig. 2, is fitted in the end of the tubular arm 4 so that the light rays projected from the lamp will be alined with the centers of the lenses 6. The conductors 8 for conveying electricity to the lamp are housed within the hollow arm or stem 4 and pass through an opening 9 provided therefor adjacent the inner end of the arm, passing thence through an opening 10 in the door and being secured to binding screws or posts 11 at the lower end of a switch housing 12 which is secured upon the inner side of the door. One of the wires 8 is grounded through the switch housing 12, while the other wire is connected with a contact member 13 of any preferred form secured within the housing 12 and adapted to be engaged by a switch arm or lever 14 pivotally mounted within the switch casing and projecting forwardly through the side of the same, as will be understood upon reference to Fig. 3.

The arm or stem 4 is provided between its ends with a lug 15 to which one end of a cable or other flexible connection 16 is attached. This cable 16 is carried upwardly to a point above the bracket 2 and then passed through an opening provided therefor in the door frame, after which it is carried downwardly within the car adjacent the inner side of the door and is attached to the lower forwardly projecting arm 17 of an angle lever which is fulcrumed upon the door, as at 18, and has its operating arm 19 extending upwardly, a knob 20 or other convenient form of handle being provided at the upper end of the said arm 19 of the angle lever. A cable or link 21 connects the outer end of the switch arm 14 with the forward extremity of the angle lever arm 17, as shown clearly in Fig. 3. The switch casing 12 and the angle lever are mounted upon a plate 22 which is secured upon the inner side of the door 3 so as to provide a firm support for the parts and also to avoid excessive wear upon the finish of the door, a stiffening base plate or lug 23 being provided upon the plate 22 to carry the fulcrum of the lever. A keeper 24 is also secured upon the plate 22 at a point in advance of the upstanding arm

of the angle lever so that, when the lever is pushed forward, it will be engaged by this keeper and prevent it from returning to its initial position until manually released.

- 5 It is thought the operation of the device will be readily understood from the foregoing description, taken in connection with the accompanying drawing. As long as the vehicle is in motion upon a straight ahead 10 path, the signal arm 4 is permitted to remain in the pendent position illustrated in Fig. 1, the operating lever and the switch lever being then in the positions shown in full lines in Fig. 3. If the operator in 15 tends to change his direction of travel or to stop, he will push forwardly upon the angle lever swinging it to the position indicated by dotted lines in Fig. 3, thereby exerting a pull through the link 21 and the 20 cable 16 upon the switch arm 14 and the signal arm 4, respectively. The signal will thus be raised to the position shown in Fig. 2 and, simultaneously, the switch arm 14 will be moved downwardly to the position 25 shown by dotted lines in Fig. 3, electrically engaging the contact member 13 and completing the circuit through the battery and the lamp 7. The lamp will then, of course, become illuminated and will serve to attract the attention of motorists coming in 30 either direction. The device may be operated during either the day or night, and

at night may be left in its raised position so as to serve as a parking lamp. The device is exceedingly simple in the construction, arrangement and operation of its parts, 35 may be applied readily to any vehicle and, when applied, may be easily manipulated. The parts inside the car are of such form that they will all lie close to the door and 40 will not offer any obstruction to ingress or egress nor will they interfere in any degree with the movements of the operator in controlling and steering the vehicle.

Having thus described the invention, I 45 claim:—

An actuating means for a signal comprising a mounting plate adapted to be secured against the inner face of a support, a bell-crank lever pivoted to said plate and having a horizontally extending arm and vertically extending arm, a flexible connecting member adapted to be passed through an opening in said support with its inner end secured to the horizontal arm of said 50 lever and its outer end connected with the signal and a latch carried by said plate for engagement by the vertical arm of said lever to releasably retain the lever in a set 55 position.

In testimony whereof I affix my signature.

PETER F. VAN HALDER. [L.s.]
